UNITED STATES PATENT OFFICE.

RAYMOND D. SMITH, OF EAST MILTON, MASSACHUSETTS, ASSIGNOR TO SHAWMUT MACHINE WORKS, INC., A CORPORATION OF MAINE.

DELAYED SELF-CLOSING GAS VALVE.

Application filed April 27, 1917, Serial No. 165,026. Renewed July 8, 1922. Serial No. 573,631.

To all whom it may concern:

Be it known that I, RAYMOND D. SMITH, a citizen of the United States, residing at East Milton, in the county of Norfolk and 5 Commonwealth of Massachusetts, have invented certain new and useful Improvements in Delayed Self-Closing Gas Valves, of which the following is a specification.

This invention relates to mechanism for 10 effecting the delayed automatic closure of gas valves in general, and particularly the delayed closure of the larger type of valve, or fuel gas-cock;—such, for instance, as is commonly used to control the gas supply to 15 the burner of a small gas water-heater.

The invention has for its general object to provide in compact and self-contained form an ordinary and approved type of gas valve and mechanism for operating the same, so 20 associated therewith, that the valve is thereby rendered manually adjustable as usual to any desired degree of opening, and such mechanism further incorporating automatic means energizable at will, by manipulation 25 of the usual valve controlling extension, whereby automatic closure of the valve, after a substantial period of delay, may be had through controlled thermo-dynamic effects;—and preferably through automatic 30 government and utilization of the gas supply to produce the heat effects necessary in securing the designed thermostatic action, all as consequent upon simple actuation of the manual valve turning means.

35 In practice, such delayed closure of the valve may take place, to advantage, after an interval of time varying, say, from five to thirty minutes after energization of the automatic means above referred to; such 40 time-interval being readily alterable by varying certain elements of the device. The very material convenience in operation offered by my improved gas valve when used in the connection above referred to is obviously that the operator is enabled to set the 45 valve for delayed closure and go about other business without having to remain, or to return, to shut off the gas at the proper time.

In the provision of a valve having the 50 characteristics above described and of an operating mechanism therefor which shall be at once simple, durable and inexpensive to produce, a particular object of the present

invention is to utilize the principles of heat transmission to produce the desired interval 55 of time in the automatic operation of the valve, for, by such principles, a delayed automatic valve action can be governed by a slight mechanical movement caused by the slow accumulation of heat in some simple 60 thermo - dynamic element, such as a fluid-filled thermostat, rather than by some comparatively complex, and mechanically retarded, motive device such as a spring-driven clock movement or the like, as is 65 customarily employed for this purpose.

As I have filed other applications for U. S. Letters Patent for thermostatic valve-controlling mechanism of somewhat similar character, I will here point out some of the 70 novel features distinguishing the present improvement from the structures and principles of operation disclosed in said other applications. In a preferred form the present arrangement involves (as do certain of my 75 other applications) the use of a main and auxiliary burner, co-operatively acting in controlling automatic extinguishment of the said main burner; but for separately governing the supply of gas respectively to each of 80 said two burners, two separate valves are herein provided,—both adapted to be actuated in predetermined operative relation by a single radially-extending control arm which in the specific embodiment herein disclosed is spring-connected to the main valve 85 to tension the same for automatic closure.

In connection with this control arm, I have herein provided a novel form of manually releasable latch device for locking said arm 90 in a position to establish the valve-closing tension, and a new function herein given to such latch device is that of serving as a trigger for conveniently tripping the thermostatically governed detent thereby to free 95 the main valve from restraint by the latter to permit undelayed valve closure through direct manipulation of the control arm.

Also novel in the present improvement is the use of a liquid-filled thermostatic disc for governing the valve detaining detent,—a laminated or flexing band type of thermostat having heretofore been employed for this purpose. The disc form of thermostat, in general, is capable of performing more 105 movement and of exerting greater force than

a band thermostat, but its incorporation within a compactly organized mechanism presents several structural problems that are effectively solved by the details of arrangement hereinafter described.

A particular mechanical feature of my improved valve controlling mechanism, and one that constitutes an important object of the present invention, resides in a novelly arranged 10 detent, which virtually constitutes an indirect lock for the valve, whereby the latter may be retained in an open position against powerful tension tending to close the same, and yet is adapted to be automatically 15 released for closure by comparatively a very weak thermostatic effort. It has developed in practice that the friction between engaging detent surfaces, which results from direct opposition by a thermostatically operated 20 detent member to the powerful valve-closing spring, imposes too great a load upon the preferred type of thermostat to enable the latter satisfactorily to trip such detent member. The novelly arranged 25 detent, above referred to, provides in compact and rugged form a simple and effective remedy for this condition, and the novel principles of the arrangement may be applied to equal advantage in apparatus that 30 employs as the detent-tripping agent a clock mechanism or other timer device that is capable of exerting only a comparatively weak force.

Other and specific objects of the invention 35 reside in the provision of a novelly arranged and novelly controlled auxiliary burner for generating the heat to be accumulated by the thermostat, in the means for causing the automatic ignition of this auxiliary burner from the flame of the main 40 water-heater burner, and in various details of construction aimed generally to conserve the heat generated by the auxiliary burner and to protect the designed heat 45 paths from operative disturbance by outside temperature conditions.

To the accomplishment of the above described objects among others hereinafter to be pointed out, my invention resides in several 50 different combinations and arrangements of elements, a preferred form of which, for illustrative purposes only, is next to be described, reference being had to the accompanying drawings in which:

Fig. 1 is a front view in elevation showing my improved delayed closing valve in open position with certain associated burner parts, including the base of a gas-and-air mixing chamber for the gas-water heater 60 burner, the wall thereof and also certain other parts being partially broken away or shown in section for clearness; Fig. 2 is a side view in elevation looking at the left of Fig. 1, and showing the mechanism casing 65 in section, a portion of the thermostat heat

conductor being broken away; Fig. 3 is a view similar to Fig. 1 showing the positions of parts when the valve is closed; Fig. 4 is also a view similar to Fig. 1, with the valve tensioned for closure but held open by the 70 thermostatically governed detent latch; Fig. 5 shows a modification in the construction and arrangement of the thermostat heat conductor and auxiliary burner parts, whereby certain useful purposes are served; Fig. 6 75 is a front elevation of the valve with the modification above mentioned part of the heat chamber wall being broken away more clearly to show the interior parts; Fig. 7 is an assembly view on a reduced scale showing the valve and water heater burner, in which view the position of the auxiliary burner relative to the latter, and also the arrangement for causing automatic ignition of said auxiliary burner are clearly shown; Fig. 8 is a sectional view through the centre 80 of the thermostat on the plane 8—8 in Fig. 2, showing the method of supporting the same.

Throughout the several views of the drawings identical parts are designated by similar reference numerals.

A valve body is shown at 10 with suitably threaded terminals 11 for connecting the same in the pipe line between the supply and the controlled water-heater burner 71, as shown in Fig. 7, only the base 9 of a mixing chamber for the gas and air delivered to the latter appearing in the other views. The usual rotative, tapered valve plug 12 is held 100 axially in its seat in said body by the spring 13 as usual, and oscillates therein to control the flow of gas by varying the rotative position of the diametrical opening 14 through the plug. In Figs. 1 and 4 this opening is 105 positioned in alignment with the gas passage 15 in the valve body 10, so that the valve is open.

A dog-plate 16, having a hub 31, is rigidly pinned to the forward end of a stem 17 of the valve plug 12, which latter is turned down at this portion to a constant diameter and carries loosely pivoted theron, between the dog-plate 16, and the valve body 10, the hub 18 of a control lever 19, provided at one 115 end with a handle 20. At the opposite end, this control lever is provided with a rearwardly extending terminal 61 for purposes to be later described. A spiral leaf spring 21 at one end 22 thereof is secured to the hub 18 and at the other end 23 to a rearward extension 24 of the dog-plate 16, so as normally to hold said extension and the control lever 19 in engagement and thereby the plug 12 and the control lever 19 in definite 120 rotative relation, but separable therefrom against tension in spring 21 in one relative direction of rotation. Frame lugs 64, 64 limit the swing of the lever 19.

The control lever 19 carries pivoted there- 130

to at 8, a combined latch and trigger member 25 formed as a three-armed lever and normally positioned by the spring 26 to engage at a catch-formed end 27 of the downwardly disposed arm 40, with a stationary lock stud 28 projecting forwardly from the valve body, thereby to lock the control lever 19 in its position shown in Figs. 3 and 4. Another of these arms 41 extends outwardly substantially in radial alignment with the control arm 19 and terminates in a forwardly extending portion 43 near the handle 20 to be conveniently operated in conjunction therewith for purposes hereinafter described. The third arm 42 is disposed oppositely the arm 40 and is operative as a trigger only in the position of the control arm 19 shown in Fig. 1 and for purposes to be described.

The dog-plate 16 carries pivoted thereto at 29, an angular strut arm 30 held yieldingly against a stop 33 on the former so that an elbow portion 34 of said strut arm normally wipes, in passing, against the abutment roller 37 loosely pivoted on a stud 38 fixed to a bracket extension 39 of the front circular support plate 36. The strut arm at its free end 6 extends rearwardly to be engaged in a certain position of the dog-plate and when the strut arm 30 is in contact with the roller 37, by a detent latch arm 35 at the catch formed end 32 of the latter. The latch arm 35 has a hub portion 44 which carries also an upwardly extending trip arm 45, and pivoted to the end of the latter is a floating trip bar 46 adapted at its free end to be engaged at certain times by the arm 42 of the lever 25 for tripping the detent arm 35 as shown in Fig. 1. The hub 44 is secured by suitable, and preferably by rotatively adjustable means (such as a set screw), to a horizontally disposed shaft 47 formed at one portion 48 thereof as a crank and journaled at its ends in a side support bracket 49 and in the bracket extension 39 respectively. At its point of greatest eccentricity the said crank portion 48 of the shaft 47 is caused to bear upon the centre of a disc thermostat 50 by the torsional tension in a spring 51 coiled about the shaft 47, and the latch lever is thus positioned, when the thermostat 50 is normally cool, to intercept the strut arm 30 as shown in Fig. 4.

The disc thermostat 50, as shown, comprises two expansible and annularly corrugated, metallic discs, sealed gas tight at their periphery and filled to suitable capacity with a thermally expansible fluid. Radially disposed ribs 52, secured at their ends by U-shaped clips 63, and having a central threaded boss 75, serve as a convenient means for mounting the thermostat by means of a screw 76 on some suitable thermally conductive metallic member, such as the upwardly extending bar 53 as shown in Fig. 8,

said bar being preferably of appreciable length for retarding the deliverance of heat to the thermostat. In Figs. 1 to 4, inclusive, the bar 53 is shown as extending upwardly and terminating in an inwardly disposed, upright, hollow cone 54, open at the bottom and provided with a small perforation 55 at its top. In vertical alignment with the cone, and beneath the same, is an upright Bunsen burner tube 56 with openings 57 for the air supply thereto, the said burner having a gas supply tapped from the main valve body gas passage 15 at a lateral outlet 58 therefrom, the said supply being controlled by a gas cock 59, arranged between said outlet and the Bunsen burner tube 56, and said cock being provided with a two-fingered operating cam 60 therefor. The cam 60 and thereby the cock 59 is adapted to be operatively engaged by the extremity 61 of the control lever 19 heretofore described.

It will be noted in Figs. 1 and 2 that the heat conducting bar 53 is not secured in direct contact with the side frame-plate 49 but is spaced therefrom by heat resistive bushings and washers, such as shown at 62 in the said figure, so that heat transmitted from the flame of the Bunsen tube to the thermostat by the bar 53 cannot readily escape from the latter to the supporting structure therefor.

In Figs. 5 and 6, the auxiliary burner and heat conductive means are shown in modified form, the said burner here comprising a downwardly extending and upwardly terminating burner tube 65 above the open end of which falls the heat receiving end 66 of a modified form of heat conducting bar 67 to which latter the thermostat 50 is secured as usual. The heat receiving end 66 is dome-shaped and has an opening 68 positioned directly over the said end of the burner tube 65. All of the parts above described are contained in a substantially closed chamber, having sufficient vent to support combustion of the small burner flame, and also having a transparent window 69 of some suitable material, such as mica, to render visible the flame.

In the above described modified structure the transmission and accumulative effect of the heat is obviously less susceptible to drafts or surrounding outside temperature conditions; and operation of the device is rendered therefore more reliable under extremely cold or drafty conditions. It will be appreciated that this modified construction embodies practically an oven with an internal source of heat, and I preferably introduce heat insulation between such oven and the rest of the structure, so that the latter may not be unduly heated during the interval of time designed in effecting the delayed operation of the device. I may better

the immunity to temperature disturbances provided by this oven by constructing the walls of the latter with a dead air space arrangement or other well known heat insulating means.

In each of the above described arrangements for generating and controlling the heat used to operate the thermostat, the auxiliary burner (when supplied with gas) is adapted to be automatically ignited by the natural rise of such gas through a suitable and unobstructed conduit therefor, as is provided by the tube 70 in Fig. 5, the said tube terminating adjacent and preferably below some point of maximum heat of the flame of the main burner 71 so as to deliver the said gas thereto. When thus ignited, the flame flashes backwardly through the tube and subsequently burns at the mouth of the auxiliary burner to supply heat for operating the thermostat. Also in each of the described arrangements, adjustment of the size of the auxiliary burner flame may be had by the screw 72.

A casing 73 is provided to house the parts and a wing nut 74 is secured to the end of the valve stem exterior of such casing to indicate the true position of the valve and to act as positive means for operating the valve in case the automatic control mechanism goes wrong.

The operation of the valve and controlling mechanism above described is as follows: Starting from a position of parts as in Fig. 1 where the valve is open and the main water-heater burner (not shown in this figure) is assumed to be ignited and in normal operation, the valve may be partially or wholly closed by manually depressing the handle 20 to swing the lever 19 toward its position in Fig. 3. At the beginning of such depression, however, the end 43 of lever 25 must be pressed upwardly toward the handle 20, which act may be conveniently performed by the fore-finger of the operator's hand, to trip the latch arm 35, which otherwise retains the strut arm 30 and thereby the valve dog 16 in valve-opening position. Upon arrival of the control lever 19 at its position as in Fig. 3, it will be locked therein by latching engagement of the arm 40 with the stud 28, and must be released from such engagement by manipulation of the lever 25 similar to that above described before the valve can again be opened.

To produce delayed closure of the valve, from its open position as shown in Fig. 1, the handle 20 is depressed as said, but without tripping the detent latch arm 35, whereupon the valve is retained open by the latter and the spring 21 is established under tension tending to close the valve. This position of parts is shown in Fig. 4, and from this figure it will be apparent that the end 61 of control lever 19 has operated cam 60

to open the cock 59 and supply gas to the auxiliary burner. Such burner thereupon ignites automatically from the heat of the main water-heater burner as heretofore described and operates to transmit heat slowly to the thermostat through the heat conducting bar 53 therefor. The interval of time required to raise the thermostat to its designed operative temperature constitutes the delay before automatic closure of the valve 75 is effected. Such closure is caused by the spring 21 when the thermostat has been axially expanded by the heat sufficiently to retract the latch arm 35 from restraining engagement with the end 6 of the strut arm 30, thereby freeing the valve dog 16.

The nature of the indirect lock provided by the co-operative arrangement of the strut arm 30, the detent latch 35 and the roller abutment 37 is such that the greater part of the powerful valve-closing tension in spring 21 is opposed by said roller abutment, and only a very small component of such tension is operative as pressure upon the latch arm 35, so that very little friction exists between the engaging parts 32 and 6 to be overcome by said expansion of the thermostat.

It will be obvious that when automatic closure of the main valve occurs, gas is thereby also shut off from the auxiliary burner although the local controlling cock 59 remains open. When the control lever 19 is displaced from its position in Fig. 3, however, the cock 59 is at once closed, so it is clear that only in the position of parts shown in Fig. 4, is gas supplied to the auxiliary burner. In some forms of the invention, I prefer to arrange the cock 59 with resilient means always tending to close the same.

It will be evident that the burner and heater parts extending upwardly and exterior of the mechanism casing in the form thereof shown in Figs. 1 to 4, inclusive, may to advantage be partially or wholly encased to protect the same from drafty conditions and to otherwise conserve the heat. The interval of time constituting the delay before automatic valve closure may be readily varied by altering the amount of engagement between the part 32 and the part 6, by adding or detracting from the heat radiating propensities of the heat conductor 53 and of the thermostat itself, by varying the magnitude of the auxiliary burner flame; by changing the cross section or material of the heat conductor, or by varying the volumetric contents or expansible properties of the thermostat.

I may avail myself of the useful advantages possessed by the hereinbefore described valve-operating mechanism, and yet utilize other means for thermally energizing the thermostat than those herein described. For instance, in place of the automatically

ignited auxiliary gas burner operating to heat the thermostat as herein described I may introduce a small capacity, by-pass water conduit which shall be arranged to 5 accommodate a branch thermo-siphon water circulation from a low point to a higher point in the ordinary domestic water boiler or reservoir, and parallel with the main circulation through the tubes or coils of the 10 gas water-heater. Such by-pass may be led at one point thereof into thermal proximity to the thermostat, so that when the water flowing therethrough becomes hot (as will be the case only when the entire volume 15 of water, or a designed part thereof, contained in the boiler becomes heated) the thermostat will be thermally and operatively energized to trip the valve retaining 20 a detent latch as described; and by providing an arrangement whereby the outlet from the said low point in the boiler to the said by-pass circulation may be made selectively 25 adjustable to different levels in the boiler, it will be obvious that my improved, delayed-closing valve may be arranged automatically to cut off the gas when any desired proportional amount of the water contained in the boiler has become heated.

The principles of the invention exemplified by the controlling arrangement herein illustrated are, of course, readily as applicable to valves for controlling the supply of gas for illuminating burners and for other useful purposes as to the particular form of 35 water-heater valve herein chosen only to demonstrate those principles; also the novel and compact arrangement of indirectly locking detent and the thermostatic means for tripping the same can be used to advantage 40 for governing the automatic movement of many other heavily tensioned devices, such as an electric switch, or pneumatic valve.

As many other modifications in detail of construction and in means for thermally energizing the thermostat may, of course, be 45 made within the scope of the principle of my invention, I do not limit such scope to the precise embodiment of the invention herein disclosed but what I claim as new 50 is:

1. A plural gas burner and controlling valve arrangement embodying, in combination; a main burner; a main valve for regulating the supply of gas thereto; mechanism 55 adapted automatically to actuate said valve; a thermostat arranged to govern the automatic actuation of said valve by said mechanism; an auxiliary burner for operatively energizing said thermostat; an auxiliary 60 conduit arranged to conduct gas from said main valve to said auxiliary burner; an auxiliary valve operating in said auxiliary conduit for regulating the supply of gas to 65 said auxiliary burner; together with common control means operating both said main

and said auxiliary valves and controlling in predetermined relation the supply of gas to each of said burners.

2. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from 70 said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each of 75 said burners.

3. A plural gas burner and controlling valve arrangement embodying in combination, a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from 90 said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each of 95 said burners.

4. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from 100 said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each of 105 said burners, said member further having resilient connection with the main valve to tension same for movement.

4. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from 110 said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each of 115 said burners, said member further having resilient connection with the main valve to tension same for movement.

4. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from 120 said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each of 125 said burners, said member having constant operative 130

- connection to said main valve and being movable into and out of actuating engagement with said auxiliary valve.
5. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from said main valve to said auxiliary burner; an auxiliary valve operating in said conduit for regulating the supply of gas to said auxiliary burner; together with a controlling member mounted for limited movement and adapted to engage with operating extensions on each of said main and said auxiliary valves for controlling in predetermined relation the supply of gas to each of said burners; said member having constant operative connection to said main valve and being movable into and out of actuating engagement with said separate valve to open the latter valve when in a position to close said main valve.
6. A plural gas burner and controlling valve arrangement embodying in combination, a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from said main valve to said auxiliary burner; an auxiliary valve operating in said auxiliary conduit for regulating the supply of gas to said auxiliary burner; together with a controlling member mounted for limited movement and adapted to engage with operating extensions on each of said main and said auxiliary valves for controlling in predetermined relation the supply of gas to each burner, said member further having resilient connection with the main valve to tension same for movement and being arranged by a single actuation thereof to energize said resilient connection and to open said separate valve.
7. A plural gas burner and controlling valve arrangement embodying, in combination; a main burner; a main valve for regulating the supply of gas thereto; mechanism adapted automatically to actuate said valve; a thermostat arranged to govern the automatic actuation of said valve by said mechanism; an auxiliary burner for operatively energizing said thermostat; an auxiliary conduit arranged to conduct gas from said main valve to said auxiliary burner; an auxiliary valve operating in said conduit for regulating the supply of gas to said auxiliary burner; together with common control means for co-operatively and simultaneously adjusting said two valves for controlling the supply of gas to each of said burners.
8. A plural valve structure embodying in combination; a master valve and manually operable means for operating the same; resilient means to tension said master valve for automatic closure; a detent and controlling thermostat therefor to govern said automatic closure; a normally inactive burner arranged in heating relation to said thermostat; an igniting arrangement for said burner; and an auxiliary valve structurally separate from said master valve and arranged to govern the supply of gas from said master valve to said burner,—said auxiliary valve being operably related to said means and arranged to be so governed thereby that gas is delivered to said auxiliary burner only when said master valve is tensioned for closure.
9. A plural valve structure embodying in combination; a master valve arranged to control both a main and an auxiliary supply of gas; manually operable means for operating said master valve; resilient means to tension said master valve for automatic closure; a detent and controlling thermostat therefor to govern said automatic closure; a normally inactive burner arranged in heating relation to said thermostat and receptive to said auxiliary supply of gas, and an auxiliary valve structurally separate from said master valve and arranged to govern said auxiliary supply of gas,—said auxiliary valve being operably related to said means and operatively governed thereby.
10. The combination with a thermostatically governed, tension-actuated, rotary device of an extension carried by said device for rotating the same; a strut arm pivoted to said extension and yieldingly held to protrude therefrom in definite radial position; a stationary, roller abutment positioned to be wiped by a portion of said arm thereby to cause the latter to yield from its normal position when passing said abutment; and a thermostat and detent controlled thereby normally arranged to engage with said strut arm while the latter is in contact with said abutment, whereby said strut arm is restrained from yielding and the said device thereby detained.
11. Detent mechanism for holding and releasing a device that is heavily tensioned to rotate about its axis embodying, in combination; an interceptive arm mounted on said device for limited swinging movement about a pivot whose axis is parallel with and eccentric to the axis of said device; a spring and co-operative stop means yieldingly holding said arm in a normal position on said device wherein the former is carried at a

- definite radial distance from the axis of the latter; an abutment positioned to intercept a portion of said arm thereby to check rotative movement of said device when the 5 arm occupies its normal position on the device;—said abutment also being arranged to cause said arm to swing retractively toward the axis of the device to permit escapement of the latter; and a retractable 10 latch separately pivoted adjacent to said device and normally positioned to engage with said arm to prevent the retractive swinging thereof when encountered by said abutment.
12. Detent mechanism for holding from 15 rotative movement, and for permitting release of, a device that is heavily tensioned to turn about its axis embodying in combination; an interceptive arm pivoted on said device in a position normally to protrude 20 a definite extent therefrom; a spring connecting said arm to said device to swing the former to its normal protruding position relative to the latter; an abutment positioned to intercept a portion of said arm 25 thereby to check rotative movement of said device when the arm occupies its said normal protruding position;—said abutment also being arranged to cause said arm to swing retractively about its pivot on said 30 device to permit escapement of the latter; and control means movable to and from a position to prevent the abutment-caused retractive swinging of said arm relative to said device for governing escapement of 35 the latter.
13. The combination with an oscillatory device of an extension carried by said device for oscillating the same; a pivoted radial arm arranged to turn said device in 40 one direction of its swing through abutting engagement with said extension; resilient connections for tensioning said device to turn in the opposite direction; an independently mounted detent pivoted for movement 45 to and from a position to engage with said device to restrain the latter from turning in said opposite direction; and a trip lever mounted on said arm in a manner to be movable relative thereto and adapted when 50 so moved to displace said detent from its said position, to prevent restraint of the device by said detent.
14. The combination with an oscillatory device of an extension carried by said device 55 for rotatively driving the same; a pivoted radial arm arranged to turn said device in one direction of its swinging movement through abutting engagement with said extension, and arranged to be separable from 60 engagement with said extension in the opposite direction of its swinging movement; a tensioned spring connecting said device and said arm to hold the latter in its said abutting engagement with said extension; a detent pivoted for movement to and from a po- 65 sition to engage with said device thereby to restrain the latter from following up said arm when the latter is separated from said extension against the tension in said connecting spring; and a combined trip and latch 70 lever mounted on said arm in a manner to move between a position to lock said arm in a position to tension said device for follow-up movement and a position to free said device from restraint by said detent to permit said follow-up movement.
15. In an apparatus employing a common operating handle for directly actuating a controlled device and for tensioning the same for automatic movement, in combination; with said handle and said device; a movable detent mounted independently of said device; means of engagement between said detent and said device whereby the former holds the latter to prevent its said automatic 80 movement; and a trigger carried by said control handle and arranged thereon normally out of operative connection with said means of engagement but adapted upon separate manipulation and by designed movement relative to said device, to actuate said means for freeing the device from restraint by said detent.
16. In an apparatus employing a common operating arm for directly actuating a controlled device and for tensioning the same for automatic movement, in combination with said handle and said device; an independently mounted detent; means of engagement between said detent and said device 90 whereby the former holds the latter to prevent the said automatic movement thereof; a second detent for holding said control handle in a position to tension said device for automatic movement; and a trigger carried by said operating arm normally out of operative relation to said means of engagement, but adapted upon separate manipulation and designed movement relative to said device to free both said operating arm and 95 said device from engagement by their respectively restraining detents.
17. Thermo - dynamic, latch - retracting means embodying in combination a thermostat comprising a shallow chamber formed 105 by two annularly corrugated discs joined at their periphery and containing a thermally expansible fluid; a flat star-shaped reenforcing plate conforming to each face of said thermostat, with clips straddling the periphery of said discs for retaining said plates; a central, threaded portion on one of said star plates for mounting the thermostat; and a latch-carrying shaft journaled in juxtaposition to the face of said thermostat 110 opposite the said star plate, and formed between its journaled ends as a crank, arranged at the point of greatest eccentricity thereof, to bear upon the center of the other star plate; together with resilient means for 115 120 125 130

maintaining said shaft in contact with the said other star plate as described.

18. A thermostatically governed, delayed closing gas valve; embodying in combination; a valve stem adapted for oscillatory rotation between valve-opening and valve-closing positions thereof; an oscillatory, radial, lever for operating said stem, pivoted thereon, and also adapted for limited swing-
5 movement between valve closing and valve opening positions; a resilient connection between said lever and said stem whereby the former is normally maintained in positive engagement with the latter in the direction of rotation for opening the valve but separable from such engagement in the opposite direction of rotation, and against the tension in said resilient connection; a strut arm pivoted to an extension of said stem and
10 20 yielding held to protrude therefrom; a stationary roller abutment positioned to be engaged by said strut arm in a valve opening position of said stem and to cause the yielding thereof when said arm is passing
25 said abutment in valve-closing movement of said stem; a detent to engage with said strut arm whereby said stem is intercepted in its said valve-closing movement; and a thermostat adapted when heated to trip said detent

and free said stem; together with a burner 30 for heating said thermostat and a gas supply auxiliary control valve for said burner; the said auxiliary valve being operatively related to said lever, to be opened thereby only in said valve-closing position of the latter. 35

19. The combination with a thermostatically governed tension-actuated, rotary device of an extension carried by said device for rotating the same; a strut arm pivoted to said extension and yielding held to protrude therefrom in definite radial position; a stationary, roller abutment positioned to be wiped by a portion of said arm thereby to cause the latter to yield from its normal position when passing said abutment; and a 40 controlling detent mechanism normally arranged to engage with said strut arm while the latter is in contact with said abutment, whereby said strut arm is restrained from yielding and the said device thereby detained. 45

Signed at Boston, Massachusetts, this 26th day of April, 1917.
